US0D1071984S

(12) **United States Design Patent** (10) Patent No.: **US D1,071,984 S**
Chuang et al. (45) Date of Patent: ** Apr. 22, 2025

(54) **DISPLAY SCREEN OR PORTION THEREOF WITH GRAPHICAL USER INTERFACE**

(71) Applicant: **Acer Incorporated**, New Taipei (TW)

(72) Inventors: **Ching-Yuan Chuang**, New Taipei (TW); **Zheng-Yan Lee**, New Taipei (TW); **Chung-Hsien Lee**, New Taipei (TW); **Hsiao-Wei Chi**, New Taipei (TW)

(73) Assignee: **Acer Incorporated**, New Taipei (TW)

(**) Term: **15 Years**

(21) Appl. No.: **29/957,224**

(22) Filed: **Aug. 13, 2024**

(57) **CLAIM**

The ornamental design for a display screen or portion thereof with graphical user interface as shown and described.

DESCRIPTION

The FIGURE is a front view of a display screen or portion thereof with graphical user interface showing our new design.

The dot-dash broken lines illustrate a display screen or portion thereof and form no part of the claimed design. The even-dash broken lines illustrate portions of the graphical user interface that form no part of the claimed design.

1 Claim, 1 Drawing Sheet
